UNITED STATES PATENT OFFICE.

WALTER J. GADSBY, OF BOSTON, MASSACHUSETTS, ASSIGNOR TO THE
ROXBURY CARPET COMPANY, OF SAME PLACE.

DESIGN FOR A CARPET.

SPECIFICATION forming part of Design No. 13,579, dated February 6, 1883.

Application filed December 13, 1882. Term of patent 3½ years.

To all whom it may concern:

Be it known that I, WALTER J. GADSBY, of Boston, in the county of Suffolk and State of Massachusetts, have invented a new and valuable Design for Carpets, of which the following is a specification.

The nature of my design is fully shown in the accompanying photographic illustration.

The design is composed of the groundwork or ornamentation of variously ornamented and shaped figures closely arranged, and the floral and foliage ornamentation partially concealing said groundwork.

I claim—

The design for a carpet, substantially as shown and described.

In testimony whereof I have signed my name to this specification, in the presence of two subscribing witnesses, this 9th day of December, 1882.

WALTER J. GADSBY.
